CLAIM

The ornamental design for a woman's garment with monitor accommodation, as shown and described.

DESCRIPTION

FIG. 1 is a three-dimensional perspective view of the woman's garment with monitor accommodation of the present invention;

FIG. 2 is a front view of the woman's garment with monitor accommodation of the present invention;

FIG. 3 is a top view of the woman's garment with monitor accommodation of the present invention;

FIG. 4 is a side view of the woman's garment with monitor accommodation of the present invention;

FIG. 5 is a rear view of the woman's garment with monitor accommodation of the present invention; and,

FIG. 6 is a bottom view of the woman's garment with monitor accommodation of the present invention.

The broken line showing of a strap in FIGS. 1-4, and 6, is for illustrative purposes only and forms no part of the claimed design.
